C. DAY & G. E. WINDELER.

FUEL PUMP.

APPLICATION FILED JUNE 13, 1912.

1,115,179.

Patented Oct. 27, 1914.

FIG. 1.

UNITED STATES PATENT OFFICE.

CHARLES DAY AND GEORGE E. WINDELER, OF STOCKPORT, ENGLAND, ASSIGNEES TO
GENERAL ELECTRIC COMPANY, A CORPORATION OF NEW YORK.

FUEL-PUMP.

1,115,179.

Specification of Letters Patent. Patented Oct 27, 1914.

Application filed June 13, 1912. Serial No. 703,395.

To all whom it may concern:

Be it known that we, CHARLES DAY and GEORGE E. WINDELER, subjects of the King of Great Britain, residing at Stockport, county of Cheshire, England, have invented certain new and useful Improvements in Fuel-Pumps, of which the following is a specification.

Our invention relates to pumps for supplying fuel to high compression internal combustion oil engines and has for its object to improve their construction and operation. Pumps of this class commonly supply fuel at a pressure greater than the compression pressure of the engine; this for example may require the pump to deliver fuel at a pressure as high as 500 pounds per square inch. Such a pump to be satisfactory in service must be well made in every particular.

The difficulties in making a single plunger pump, while many, are not so great as in making multiple plunger pumps. In the latter case great difficulty is experienced in boring the cylinders and drilling the cross-heads with the exact pitch distance between them, and to so position the cylinder bores and crosshead holes when assembled that they are strictly alined. In this connection it is to be borne in mind that there is no clearance between the plungers and cylinder walls. We overcome this trouble by so arranging the plungers that they are self-aligning or self-centering in the crosshead or other means which actuates them.

Another feature of our invention is directed to a means for quickly rendering the pump inoperative to shut down the engine in case of trouble or otherwise.

Other features of our invention will be referred to later.

In the accompanying drawing is illustrated one of the embodiments of our invention, wherein—

Figure 1 is a vertical section of a four-cylinder fuel pump; Fig. 2 is a view in front elevation thereof; Fig. 3 is a detail view showing the normal means for actuating the suction valve of the pump; Fig. 4 is a detail view showing a means for putting the suction valves out of operation, to shut down the engine, and Fig. 5 is a perspective view of one of the discharge valves.

6 indicates the main body of the pump that is secured by bolts or other means to

the engine frame 7. The lower part of the casing contains a supply chamber 8 which is filled with oil from a supply pipe 9 leading to a tank. Air is admitted to the pipe and chamber by the pipe 10. The bottom 60 of the casing is provided with a removable cover 11 having an oil trough 12 to receive all leakage which is carried off by a pipe 13. In the casing are as many cylinders 14 as are desired, usually one for each engine cylinder, said pump cylinders being 65 equally spaced and lying in the same vertical plane. In some cases it will be satisfactory to form the cylinders directly in the casing itself, as for example where good 70 dense castings can be obtained. A better arrangement, although somewhat more expensive, is to provide each cylinder with a liner 14^a which can be hardened to reduce 75 wear and later ground externally to exact 76 size to fit the opening in the casting. This is very advantageous where the casting contains small blow holes or other imperfections. Without such a device the whole 80 casting would have to be discarded and these are expensive. Whichever way the cylinder is made it should be carefully reamed to exact size.

In each cylinder is a hardened and ground plunger 15 that is snugly fitted to the cylinder wall or liner and is provided with 85 small grooves 16 to reduce leakage. The plunger passes through a stuffing box 17 of suitable construction which also holds the liner in place. The upper end of each plunger 90 is provided with an enlargement 18 where it passes through the actuating cross-head 19. The upper end of the enlargement terminates in a head 20 having a flat 95 under side which engages a finished surface on the upper side of the crosshead. The lower end of the enlargement is threaded to receive the nut 21 and between the nut and a finished surface on the under side of 100 crosshead is a hardened and ground washer 100 22 to receive the downward thrust. The washer and head 20 are closely and nicely fitted to the crosshead so that there is no 105 lost motion in a vertical direction. After the parts are properly fitted the nuts are held against rotation by cotter pins. It will be noted, however, that the enlargement 18 does not fill the hole in the cross-head, a small clearance being left all around 110 it. This is to permit of the plunger being 115

guided by the cylinder wall, thereby compensating for faulty alignment or machine work. At this point it is well to bear in mind that the crosshead also has to be guided in its movements, and that the guides have to be machined and mounted on the frame 7. Of course the parts are machined as accurately as possible and are also mounted as accurately as possible, still the opportunities for error are great, due to very exact requirements, and therefore a limited amount of play between the plunger and the crosshead is of the utmost importance. All of the plungers are similarly constructed.

The crosshead may be of any suitable construction provided it is strong and can be well guided. It is provided with as many equally spaced holes as there are plungers, the top and bottom surfaces coöperating with the plunger parts being carefully finished. The back of the crosshead is enlarged to form a good support 23, and said support moves vertically in guides 24. The crosshead is also provided with two cheek pieces 25 through which the removable pin 26 extends, said pin connecting the lower end of the eccentric rod 27 and the crosshead for actuating the plungers. The pin is normally held in place by the pivoted latch 28 that enters a small groove 29 therein. By removing the pin 26 swinging the eccentric rod 27 out of the way, and mounting the lever 30 in place as shown by dotted lines with its pin in the place of pin 26, the pump can be actuated by hand to fill the pipes leading to the pulverizers of the engine and force out any air which may be contained in the system, after which the parts are replaced and the engine will be ready for operation. The crosshead is driven by an eccentric 31 that is mounted on the end of the shaft 32. Motion from the eccentric is transmitted to the cross head by the rod 27 and the eccentric strap 33.

Each pump is provided with a suction valve 35 that is located within a holder 36, the latter having a conical end which fits a similarly shaped bore in the pump casing. The holder is held in place by a hollow nut 37. The lower end of the holder is finished internally to form a guide for the cap or cover 38 containing the lower end of the valve spindle. The cap is hardened to reduce wear. Between a fixed shoulder on the holder and the top of the cap is a coiled compression spring 39 that tends at all times to move said cap downward and permit the suction valve to seat. Extending longitudinally of the oil containing chamber at the bottom of the pump casing is a shaft 40, having squared portions and mounted thereon are arms or tappets 41, Fig. 3, each of which has an adjusting screw 42 and check nut whereby the timing of the

lift of the valve by the governor can be changed. The arms are arranged in pairs on the same hub, as best shown in Fig. 2, and located at opposite ends of the hub are valve lifters for putting the pumps out of operation as will be referred to later in connection with Fig. 4. The casing is provided with a removable door 43, Fig. 1, by means of which access is had to said valve tappets.

The tappet carrying shaft is mounted in suitable removable bearings 44 located in the side walls of the casing, said shaft also being provided with a suitable stuffing box 45 to prevent leakage. On the left hand end of the shaft is mounted an arm 46, Figs. 2 and 3 by means of which the shaft is rocked or vibrated with a constant length of stroke by the reciprocation of the pump plungers but the region of said vibration is changed by the speed governor. To this end the arm 46 is connected by a rod 47 to a lever 48, one end of which is pivotally connected to and vibrated by the crosshead 19. The other end of the lever is connected to a speed governor actuated rod 49. It will therefore be seen that as the cross-head moves up and down the tappets will be similarly moved. As the governor rod moves up or down with a change in speed the position of the fulcrum 50 of the lever 48 will be changed and hence the region of movement of the tappets. As the fulcrum 50 is moved downward by the speed governor (not shown) the suction valve 35 will close earlier on the discharge stroke 100 of the plunger and hence a greater amount of oil will be delivered by the pump to the pulverizer. If the fulcrum is moved upward less oil will be delivered. It is to be understood that so long as the suction valve is held off of its seat the oil displaced by the plunger will be returned to the supply chamber 8 from which it was received on the suction stroke. Each pump is also provided with two discharge valves 51 and 52 arranged in series so as to prevent the oil from returning to the cylinder space on the suction stroke. In some cases one valve will suffice but the two valve arrangement is better because the likelihood of leakage is less. The valves are or may be similar in construction and are best shown in Fig. 5. The valve is hollowed out at 53 to receive the spring 54, Fig. 1, and is provided with external guides 55 that have rounded faces arranged to fit into the bore of the holder 56 for the outer valve, and the bore within the casing 6 for the inner valve. The upper end of the holder is provided with a nut 57 to limit the movement of the valve and prevent the escape of oil. The holder for the upper valve acts as a device to limit the upward movement of the lower valve. The nut 57 forms a part of a hollow fitting which re-

ceives the pipe 58 leading to a pulverizer on the engine. The lower end of each valve is provided with a beveled face 59, and orifices 60 through which the oil flows when the valve is lifted from its seat.

Between the two discharge valves and leading to the outside of the casing is a port or passage 61 that terminates in a fitting 62 containing a needle valve 63 that is actuated by a handle 64. Extending downwardly from the fitting, and controlled by the needle valve is a small pipe having a beveled end whereby the flow of oil can be observed, and whereby the danger of the end being plugged and unnoticed is obviated. Below the end of the pipe is a trough 66 for receiving oil and conveying it back to the source. The trough is formed partly by the casing 6 and partly by the wall of the removable door 43, said door being removable to give access to the valve tappets and lifters. The needle valve and its controlled passage form a by-pass which shunts the main delivery pipe 58 leading to the pulverizer. Hence when said valve is open all of the oil from its cylinder will flow through the pipe 55, following the path of least resistance, and none will be delivered to the pipe 58 and its pulverizer. By this exceedingly simple and effective arrangement a cylinder of the engine can be cut out of service when desired. Or by opening two or more needle valves two or more cylinders may be cut out. Obviously this feature is applicable to any number of engine and pump cylinders.

The suction valve and the lower discharge valve open into the horizontal passage 67 which forms the communication with the pump cylinder. This is made by drilling into the casting from one side. The hole is afterward closed by a screw threaded plug 68. By removing the plug the condition of the suction valve can be observed.

It is sometimes necessary or desirable to shut down an engine quickly, and since the pump is the thing which supplies fuel to the engine it follows that if this can be stopped the engine will stop. It is impractical to disconnect the pump actuating mechanism from the engine proper on account of mechanical complications. To avoid this a means is provided for rendering the suction valves of the pumps inoperative, and this in a simple and effective manner, said means under normal condition being idle and imposing no load or restriction on the governor, valves or pump structure. Loosely slotted on the horizontal tappet shaft 40, Fig. 4, are as many lifters 70 as there are suction valves. These lifters are made in the form of small discs each having a rounded end 71 that is adapted to en-

gage the cap 38 of the suction valve and raise it, the other end fitting into a forked arm 72 that is rigidly mounted on the spindle 73. The spindle 73 extends horizontally of the casing 6 and is supported at its ends 70 in suitable bearings and a stuffing box carried by the side walls. Mounted on one end of the spindle is a handle 74 which carries a spring pin 75 at its free end, said pin being arranged to enter one or the other of 75 two holes 76 and 77 in the casing. When the handle is raised and the pin is in the upper hole 76 the arm 72 occupies the position shown in dotted lines in Fig. 3 and full lines, Fig. 1, but when the handle is depressed and the pin is in the lower hole 77 the arm 72 occupies the position shown in Fig. 4 and the lifters have engaged and raised all of the suction valves from their seats. Under these conditions all of the oil 80 displaced by the plungers flows back through the suction valves to the chamber 8 from whence it came and therefore no oil is being supplied to the pulverizers. It will be observed that under these conditions the 85 engine must stop for want of fuel, that the governor has no control of the apparatus for the time being, that the relation of the parts of the governor mechanism itself have in no way been changed nor has the driving mechanism of the pumps been altered. To restore the parts to normal working condition after the engine is shut down the handle 74 is merely shifted to its upper position.

In so far as the means for connecting the 100 pump plungers to the cross-head is concerned it is applicable to single plunger pumps because the alining difficulties will still be present. In so far as the means for shutting down the engine is concerned it is 105 evident that it is not necessarily limited to the arrangement shown but is capable of wider application. So also the needle valves for by-passing the pumps.

Certain of the features of our invention 110 are not claimed herein because they form the subject matter of our divisional application, Serial No. 780,106 filed July 21, 1913.

In accordance with the provisions of the Patent Statutes, we have set forth what we 115 believe to represent the best embodiment of our invention; but it is to be understood that the drawing is only illustrative and that our invention can be carried out by other means.

What we claim as new, and desire to secure by Letters Patent of the United States is:—

1. In a fuel pump, the combination of a plurality of cylinders, plungers therefor, a suction and a discharge valve for each cylinder, tappets for normally controlling the suction valves, a pivoted support common to all the tappets, a means for turning the support to bring the tappets into engagement with the suction valves, a lifter for each suc- 125

tion valve, said lifters being normally idle, and means for moving them to raise the suction valves from their seats.

2. In a fuel pump, the combination of a plurality of cylinders, plungers therefor, suction and discharge valves for the cylinders, tappets for normally controlling the suction valves, a support for the tappets, lifters for the suction valves loosely mounted on the support, a plurality of means for actuating the lifters, and a device for moving all of said means simultaneously.

3. In a fuel pump, the combination of a casing having a fuel supply chamber in the bottom, a cylinder in the casing, a plunger in the cylinder, a suction and a discharge valve for the cylinder; a spindle journaled in the walls of the chamber, a tappet fixed to the spindle for lifting the suction valve from its seat when the spindle is turned, a lifter arm for the suction valve loosely journaled on said spindle, a member pivoted in the

casing, and means carried by said member for turning the lifter arm to lift the suction valve from its seat.

4. In a fuel pump, the combination of a casing having a fuel supply chamber in the bottom, a plurality of cylinders in the casing, plungers therefor, a suction and a discharge valve for each cylinder, a shaft journaled in the casing, tappets fixed to the shaft for normally controlling the suction valves, lifters for the suction valves loosely pivoted on said shaft, a second shaft parallel to the first named shaft, and means carried by the said shaft for simultaneously lifting all said lifters.

In witness whereof, we have hereunto set our hands this 23rd day of May, 1912.

CHARLES DAY. [L. S.]
GEORGE E. WINDELER. [L. S.]
